UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF DELAWARE.

SLIDING DOOR FOR MOTOR-VEHICLE¹

1,193,707.

Specification of Letters Patent.

Patented Aug. 8, 1916.

Original application filed February 16, 1915, Serial No. 8,465. Divided and this application filed September 30, 1915. Serial No. 53,272.

To all whom it may concern:

Be it known that I, ALFRED F. MASURY, a citizen of the United States, and a resident of the borough of Manhattan of the city of 5 New York, in the State of New York, have invented certain new and useful Improvements in Sliding Doors for Motor-Vehicles, of which the following is a specification, reference being had to the accompanying 10 drawings, forming a part hereof.

In Patent No. 1,180,730, dated April 25, 1916, granted to the present applicant on an application of which this is a division, there are pointed out, at some length, the advantages of a sliding door for automobiles, and particularly for motor trucks and commercial vehicles. While it has been proposed heretofore to employ doors which will slide horizontally into a concealed position within 20 the walls of the body of a vehicle, it has never been proposed, so far as is known, to provide a door which shall slide vertically into and out of operative position. It is natural that such construction has never 25 been employed when the structural difficulties of providing a sightly door which may be lowered vertically into a concealed position, are considered.

The present invention has for its object 30 to provide a door which shall be slidable vertically from closed position into a concealed position where it is inoperative and to provide, in association with said door, suitable means for guiding the same in its 35 travel so as to hold it effectively against derangement and protect it against marring.

The invention has for a further object 40 to adapt certain of the usual elements of an automobile to new uses in association with the improved door.

A further object is to provide improved 45 means for retaining the door in closed position and for releasing the same to permit it to drop gravitally into open position.

A preferred embodiment of the invention 50 will be described in connection with the accompanying drawings, in which—

Figure 1 is a fragmentary view in side elevation of a part of the body of a truck 55 showing a vertically slidable door. Fig. 2 is a fragmentary view in horizontal section taken on the plane indicated by the line 2—2 of Fig. 1 and looking in the direction of the arrows. Fig. 3 is a sectional view

through the door shown in Fig. 1 and taken 55 on the plane indicated by the line 3—3 of that figure and looking in the direction of the arrows.

The body *a* of the vehicle illustrated is provided with vertical jambs *b* for the improved vertically sliding door *c*, these jambs being formed as channels to receive the edges of the door in sliding engagement. The door *c*, as shown in Fig. 3, may be formed of sheet metal stamped into appropriate form and provided with a convenient handhold *c'* adjacent the top edge whereby the door may be grasped by the operator and slid upwardly to its closed position in which it is retained by any suitable releasable retaining means. In the illustrated embodiment such means are shown as comprising a sliding bolt *d* mounted in the floor *a'* of the car body and adjacent the sill of the door and arranged, when in extended position, to enter a suitable opening *c''* in the wall of the door and thereby maintain the door in raised position. This bolt *d* may be retracted conveniently by any suitable devices, herein illustrated as consisting of an 80 elbow lever *e*, one arm of which engages the bolt and the other arm of which is engaged by a pin *f* located within convenient reach of the foot of the driver whereby the bolt *d* may be retracted by pressure of the foot. 85 Normally the bolt is held in its extended position by means of a suitable spring *g* operatively engaged with the bolt, as through the elbow lever *e*.

In the improved construction, the brackets *h* for supporting the usual step *i* have been attached to the underside of the car in general alinement, respectively, with the channels *b* and the proximate faces of these brackets have been grooved or channeled, as 95 at *h'*, to form virtual continuations of said channels *b*. At the lower edge of the grooves *h'* are formed in the brackets *h* suitable shoulders *h''* on which the lower edge of the door *c* rests when the door is in lowered 100 position. It will be evident that when the bolt *d* is retracted, the door may be lowered in the guide-ways formed by the channels *b* and *h'* and, it is to be noted that the lower guide-ways *h'* are preferably of such length 105 as to permit the upper edge of the door to drop below the door sill *a''*. In furtherance of the general objects of the invention as re-

gards the sightliness of the improved door, the outer wall of the body *a* of the vehicle has been extended downwardly to the step *i* so as to form a slightly shield behind which 5 the door moves to its lowered position. In this way, not only is the appearance of the body unbroken by the door when in lowered position but the continuity of the exposed surface is absolute when the door is raised. 10 The jambs *b*, of course, are preferably of such form as to maintain this continuity so that when the door *c* is closed, no open joints are to be seen, as is usual.

The simplicity of construction, the sightlessness of the appearance of the body both 15 when the door is lowered and when it is raised, and the ease of operation thereof, especially during the lowering where the door moves downward gravitally, are all advantages peculiar to the door and serve to distinguish it from those which slide horizontally.

Changes in details may, of course, be made 20 without departing from the scope of the invention which is determined with greater particularity by the appended claims.

I claim as my invention:

1. In combination with the body of a motor vehicle, a door moving vertically to close 30 the usual doorway in the body, and devices to guide the door loosely in its vertical movement to opened or closed position, said devices comprising channels formed in the jambs of the doorway and separate channels 35 mounted beneath the door sill and forming respectively virtual continuations of the channels in the jambs and a wall for the vehicle body carried downward over said guide channels to conceal the same and to 40 conceal the door when the latter is dropped to opened position.

2. In combination with the body of a motor vehicle, a door movable vertically to close the usual doorway in the body, chan-

nels formed in the jambs of the doorway to 45 guide the door loosely in its vertical movement, and step brackets secured to the body below the door sill and having guide channels formed therein to constitute virtual continuations of the channels in the jambs. 50

3. In combination with the body of a motor vehicle, a rigid door movable vertically to close the usual doorway in the body, devices to guide the door loosely in its vertical movement to opened or closed position, 55 and releasable means to hold the door in raised position, said means being operable to permit the door to drop gravitally to opened position and a wall for the body carried downward to conceal the door when it is 60 dropped to opened position.

4. In combination with the body of a motor vehicle, a door movable vertically to close the usual doorway in the body, channels formed in the door jambs to guide the door 65 loosely in its vertical movement, step brackets secured to the body below the door sill and in substantial alignment, respectively, with the channels in the jambs and having guide channels formed therein to constitute 70 virtual continuations of the channels in the jambs, the last named channels being provided with shoulders to limit the downward movement of the door, a handhold formed in the upper edge of the door to permit the 75 same to be raised conveniently, a spring-pressed latch to engage the door when in raised position, a foot rod in operative engagement with said latch and operable to retract the same and permit the door to 80 drop gravitally to opened position and a wall for the body carried downward over said guide channels to conceal the same and to conceal the door when the latter is 85 dropped to opened position.

This specification signed this 28th day of September A. D. 1915.

A. F. MASURY.
